ADJUSTABLE COMBINATION STAND FOR
KNITTING MACHINESWillis A. Ingalls, Syracuse, N. Y., assignor to
Tompkins Bros. Co., Syracuse, N. Y., a corpora-
tion of New York

Application March 25, 1942, Serial No. 436,194

17 Claims. (Cl. 66—79)

This invention relates to improvements in knitting machines, and more especially to an improved adjustable stand assembly, for supporting the various equipment such as burrs (sinker, clearing, backing, etc.), pressers and the like, which are commonly used in connection with circular spring needle knitting machines.

These knitting machines, as heretofore constructed, generally include a rotatable needle cylinder mounted upon a bed for rotation about a vertical axis. According to one well known type of machine, there is attached to the bed of the machine, below the needle cylinder, a slotted mounting ring which serves to support the usual stands and other equipment which are necessary for the feeding and manipulation of the thread, pressing the needle beards, etc., as usually performed in the knitting of the fabric.

For many years, it has been the practice with such machines to employ a separate stand for practically each piece of equipment supported by the mounting ring, with the result that the equipment is crowded together, making it exceedingly difficult to gain access to certain of the parts for purposes of adjustment as may be required from time to time. In addition, such an arrangement requires a greater length of time to set up, as well as to adjust the various individual parts for satisfactory performance of their respective functions and operations; and the range of adjustment of the parts is at best very limited, and in some cases, nil.

With the foregoing in view, I have developed a new type of adjustable stand which facilitates and greatly simplifies the adjustment of the usual equipment hereinbefore referred to, while at the same time being very compact so as to afford more room to permit the mounting of additional equipment about the needle cylinder when required, and affording convenient access to all of such equipment.

Another object of the invention is to provide a novel combination stand which embraces a plurality of stands or supports in a single unit, capable of being attached to the usual slotted mounting ring or other fixed support, by a single slotted link or equivalent connecting means, preferably permitting both circumferential and radial adjustment of the combination stand as a whole, relative to the needle cylinder.

My invention additionally contemplates as a further object, the provision of a unitary combination or multiple stand assembly, wherein certain of the individual stands, at least, are both laterally as well as radially adjustable relative to

the needle cylinder, and independently of each other and of the adjustment of the unitary assembly as a whole.

A still further object of my invention is to provide a stand having one or more brackets adjustably attached thereto so as to allow adjusting movement of said brackets in one imaginary plane, and each of said brackets having another bracket adjustably attached thereto for adjusting movement in another imaginary plane generally perpendicular to the first plane, said last mentioned brackets each removably receiving and supporting another stand, while permitting angular adjustment of said latter stand.

Other and further objects of the invention will be hereinafter described, and the novel features thereof defined by the appended claims.

In the drawings:

Figure 1 is a fragmentary vertical sectional view taken through the needle cylinder and slotted mounting ring of a typical circular knitting machine, with certain other usual parts of the machine omitted, and showing in side elevation my new adjustable combination stand assembly as contemplated by my invention, and as employed for adjustably supporting a sinker tube in operative relation to the needle cylinder;

Figure 2 is a fragmentary view in top plan, of the parts of Figure 1, with one of the stands omitted;

Figure 3 is a view in end elevation, showing a fragmentary portion of the slotted mounting ring, the slotted link being in section, and the combination stand having the assembled form to provide three individual stands, with the sinker tube and needle cylinder omitted;

Figure 4 is a view in side elevation of the center or sinker tube stand per se;

Figure 5 is an end elevational view of one of the angular laterally adjustable slide brackets which is directly connected with the center stand of Figure 4;

Figure 6 is a view of the bracket of Figure 5, as projected from Figure 7;

Figure 7 is a sectional view taken on the line 1—1 of Figure 5;

Figure 8 is a view in end elevation of the outer radially adjustable slide bracket which is connected to the bracket of Figures 5 to 7;

Figure 9 is a view in side elevation of the bracket of Figure 8, as viewed from the right-hand side thereof;

Figure 10 is a view in end elevation of a modified form of stand, generally corresponding to the stand of Figure 4, but being substantially taller;

Figure 11 is a view in side elevation of the modified stand of Figure 10;

Figure 12 is a view in side elevation of the sinker tube assembly which is shown only in fragmentary form in Figures 1 and 2; and

Figure 13 is a view in side elevation of a modified form of presser stand assembly.

Like reference characters designate corresponding parts in the several figures of the drawings wherein 1 generally denotes a conventional rotatable needle cylinder of a typical circular knitting machine, said needle cylinder having mounted thereon the usual ring of spring needles 2 which are attached thereto by the needle caps 3. As shown in Figures 1 and 2, the needle cylinder is disposed for rotation about a vertical axis, and it will be understood that it lies above the usual bed of the machine (not shown).

Such machines, of which the illustration herein is general, are sometimes provided with a slotted mounting ring 4 which is attached to the bed of the machine at a point below the needle cylinder as best shown in Figure 1. This mounting ring serves to support the stands and various equipment which are mounted about the needle cylinder for coaction with the needles in the performance of the knitting operations.

According to my new stand construction to which this application is primarily directed, I attach the stands to the slotted mounting ring 4, in single or multiple units as the case requires, said attachment being effected in the conventional manner by means of a slotted link 5 extending radially outwardly from the mounting ring 4 and adjustably secured thereto by a bolt fastener 6 extending through the slot 7 in the mounting ring 4 and the slot 8 in the link 5. By loosening the bolt 6, the slotted link 5 can be adjusted both circumferentially as well as radially, relative to the mounting ring 4 and needle cylinder, as will be obvious.

As shown in Figures 1 to 4, my new stand assembly includes a main stand 9 which is adapted to rest upon the upper side of the slotted link 5, the lower end of the stand being preferably milled flat to seat upon the slotted link without rocking. Attachment of the stand 9 to the slotted link 5 is preferably accomplished by means of a bolt 10 passing through the slot 8 of the link 5, into the lower end of the stand which is provided with a threaded aperture to threadedly receive the bolt 10. By loosening the bolt 10, the stand 9 may be adjusted longitudinally along the slotted link 5, that is, radially respecting the needle cylinder, independently of the radial adjustment afforded by adjusting the link 5 itself on the mounting ring 4 as previously described. In the construction shown in Figures 1 to 4, the stand 9 extends upwardly to a point in the zone of elevation of the needle cylinder above the bed of the knitting machine, and the upper end of the stand is forked or bifurcated to provide a pair of laterally spaced vertical arms 11, 11. Each of the arms 11, 11 is preferably provided on its inner face with a shoulder 12 extending vertically thereof, for cooperation with a guide 13 provided on the inner face of a depending bracket 14 forming a part of the piece of equipment which is to be mounted on the stand, such as a sinker tube assembly 15. The guide 13 is of such width as to lie between the forked arms 11, 11 of the stand 9, but affording sliding engagement therewith to permit vertical adjustment of the bracket 14 relative to the stand 9. A bolt 16 extending through the bracket 14,

and having an enlarged head 17 spanning the space between the arms 11, 11 of the stand 9, serves to clamp the bracket 14 to the stand in its vertically adjusted position, while allowing quick and easy adjustment of the elevation of the sinker tube 15 on loosening the clamping bolt.

The details of the sinker tube assembly are best shown in Figure 12 of the drawings, but it is to be understood that the invention is not limited to this precise construction. It suffices to explain that the sinker tube assembly includes a spring-pressed bar or rod 18 projecting therefrom towards the needle cylinder, and onto the end of which is adapted to be secured a burr bracket 19 having a collar 20 at one end to receive the end of the rod 18. A set screws 21 serves to attach the burr bracket 19 to the rod 18. At the opposite end of the burr bracket, there is provided a stud 22 on which is rotatably mounted a sinker burr designated 23 and shown in broken lines in Figure 1. This sinker burr may be of conventional construction, embodying a plurality of blades, one of which is shown in outline at 24 in Figure 1. The blades 24 of the sinker burr mesh with the needles 2 on the needle cylinder 1, causing the sinker burr to rotate on the stud 22, responsive to rotation of the needle cylinder in the conventional manner. This meshing relation can be conveniently adjusted by adjusting the position of the stand 9 on the slotted link 5, and/or by adjusting the slotted link 5 relative to the mounting ring 4, in the manner hereinbefore described. Other burrs, such as clearing and backing burrs and the like, may be substituted for the sinker burr 23, or may be similarly mounted on other stands arranged at suitable positions about the needle cylinder for coaction with the needles in the proper sequence.

Referring now to Figures 3 to 9, it will be seen that the outer vertical face of the stand 9 is provided with a pair of vertically spaced tongues 25, 26 projecting outwardly from the surface thereof and extending transversely across the face of the stand near its lower end. At the center of each tongue, I provide the threaded openings 27, 28 to receive the respective bolts 29, 30. Coacting with the respective tongues 25, 26 are slide brackets 31, 32 which are mounted on the stand 9 for horizontal sliding movement. The brackets 31, 32 are identical in construction, and one of the same, 32 for example, is shown in detail in Figures 5 to 7. As will be seen from these latter figures, the bracket 32 is angular in form, providing two arms 33 and 34 arranged perpendicular to each other. The arm 33 is slotted at 35 to receive the clamping bolt 30 therethrough and permit horizontal sliding adjustment of the bracket 32, the rear face of this arm being channeled at 36 to receive the tongue 26 on the stand 9, and by coaction therewith, to guide the bracket in its horizontal sliding adjustment. The outer face of the arm 34 is provided with an elongated protuberant guiding tongue 37, and is further provided with a plurality of threaded openings 38 at spaced points in the length thereof to receive a clamping bolt 39 by which a second bracket 40 is attached to the bracket 32 for horizontal sliding adjustment in a direction normal to the sliding adjustment of the bracket 32, the bolt 39 being selectively receivable in the apertures 38.

The details of the bracket or cross-slide 40 are shown in Figures 8 and 9, from which it will be

observed that the cross-slide is provided with a channel 41 to receive the tongue 37 on the arm 34 of the bracket 32, this channel 41 and tongue 37 having a sliding fit with each other to guide the cross-slide in its adjusting movement relative to the bracket 32. The cross-slide is also slotted at 42 to receive the clamping bolt 39 therethrough, thereby allowing a limited sliding adjustment of the cross-slide for each position of the bolt 39 in the selective openings 38.

The cross-slide 40 is laterally offset at one end as indicated at 43, and this offset is provided with a vertical socket or opening 44, preferably cylindrical in cross section, to receive the lower end 45 of another short stand 46, the upper portion of which generally corresponds to the construction of the stand 9. The lower end 45 of the short stand 46 is preferably cylindrical in form to snugly fit into the opening 44 in the cross-slide 40, and the cross-slide is preferably provided with a set screw 47 which, on tightening the same against the end 45 of the stand 46, serves to restrain this stand against angular movement and against vertical displacement from the cross-slide. By loosening the set screw 47 the short stand 46 may be angularly adjusted in a manner which may be obvious. The short stand 46 may be utilized in the same manner as the stand 9, to support other burrs such as clearing and backing burrs, pressers, or other equipment which are usually employed in association with the sinker burr 23 hereinbefore described.

Again referring to Figure 3, it will be seen that a duplicate of the cross-slide 40, designated 48, is attached to the slide bracket 31, by means of a clamping bolt 49, and another short stand 50 is mounted in the cross-slide 48 and secured thereto by a set screw 51, in the same manner described above. In this manner, as many as three stands may be combined into one combination stand unit, and attached to the slotted mounting ring 4 by a single slotted link 5. Where the conditions do not require the use of all three stands, one or both of the short stands 46, 50, together with their adjusting slides, may be removed, and the stand 9 used alone if desired. However, when used in multiple, the stands are conveniently located in compact parallel relation to each other, and are independently adjustable both laterally respecting one another, as well as radially respecting the needle cylinder, in addition to being adjustable as a unit, both radially and circumferentially respecting the needle cylinder, all of which contributes to the ease of assembly and adjustment of the knitting machine equipment, and to the high over-all efficiency of the knitting machine.

Referring to Figures 10 and 11, I have shown a modified form of stand 9' which may be substituted in lieu of stand 9 in Figures 1 to 4, stand 9' being substantially taller than stand 9 and permitting the attachment thereto of additional equipment besides the sinker tube 15, as is sometimes preferred. In other respects, stand 9' generally corresponds to stand 9, and is provided with guide tongues 25' and 26' for coaction with brackets 31, 32.

In Figure 13, I have shown a special form of presser stand which may be substituted in lieu of either of the short stands 46 or 50 hereinbefore referred to. This presser stand includes a spring-pressed bar or rod 52, carrying at its inner end a bracket 53 for receiving a presser (not shown) of conventional construction. The lower

end of the presser stand assembly of Figure 13, is reduced in size as at 54 and is preferably circular in cross section to permit the same to be received in the vertical opening in the cross-slides

5 40 or 48. The part 54 is preferably formed as an integral part of the presser tube and is elongated to allow for convenient vertical adjustment of the presser stand assembly when the set screw 47 or 51 is loosened. In adjusting the presser stand assembly shown in Figure 13 or the short stands 46 and 50 shown in Figures 1 to 3, the stands are preferably angularly disposed in their sockets so that the equipment carried by these stands will extend towards the needle cylinder in 10 a generally radial direction as indicated by the broken lines *a* and *b* in Figure 2.

While the specific details have been herein shown and described, the invention is not confined thereto, as changes and alterations may be 20 made without departing from the spirit thereof as defined by the appended claims.

I claim:

1. In a knitting machine having a needle cylinder and a fixed support extending about the axis of said needle cylinder at a point below the cylinder, a stand adjustably carried by the fixed support for adjustment circumferentially and radially relative to the needle cylinder, a bracket slidably connected to said stand for adjustment 25 laterally relative thereto, a second bracket slidably connected to said first bracket for adjusting movement perpendicular to the adjusting movement of the first bracket, and a second stand carried by said second bracket and disposed at 30 one side of the first mentioned stand.

2. Apparatus as defined in claim 1, wherein the first stand and the brackets are respectively provided with coacting guide means for guiding the brackets in their adjusting movements.

3. Apparatus as defined in claim 1, wherein the first stand and the brackets are respectively provided with coacting tongue and groove means for guiding the brackets in their adjusting movements.

4. Apparatus as defined in claim 1, wherein the first stand and the brackets are respectively provided with coacting guide means for guiding the brackets in their adjusting movements, and each of the brackets is slotted to receive a fastener therethrough to adjustably clamp the first bracket to the first stand and the second bracket to the first bracket.

5. Apparatus as defined in claim 1, wherein the second stand is provided with a cylindrical part 55 which is receivable in a corresponding opening provided in the second bracket, in combination with means for restraining said second stand against rotation in and displacement from said second bracket.

6. Apparatus as defined in claim 1, wherein the second stand is provided with a cylindrical part which is receivable in a corresponding opening provided in the second bracket, in combination with set screw means for restraining said second stand against rotation in and displacement from said second bracket.

7. In a knitting machine having a needle cylinder and a slotted mounting ring disposed below 70 said needle cylinder and extending about the axis thereof, a slotted link extending radially outwardly from said slotted mounting ring and adjustably connected thereto by a fastener means extending through the respective slots thereof, a stand carried by the slotted link aforesaid and

adjustably connected thereto by another fastener means extending through the slot in said link, said stand extending upwardly from the slotted link in outwardly spaced relation to said needle cylinder and terminating near the plane of elevation of the needles on the needle cylinder, an additional stand carried by said first stand at one side thereof, and means interconnecting said stands for adjusting the second stand towards and away from the first stand and towards and away from the needle cylinder.

8. In a knitting machine having a needle cylinder and a slotted mounting ring disposed below said needle cylinder and extending about the axis thereof, a slotted link extending radially outwardly from said slotted mounting ring and adjustably connected thereto by a fastener means extending through the respective slots thereof, a stand carried by the slotted link aforesaid and adjustably connected thereto by another fastener means extending through the slot in the link, said stand extending upwardly from the slotted link in outwardly spaced relation to said needle cylinder and terminating near the plane of elevation of the needle on the needle cylinder, a pair of additional stands carried by the first mentioned stand at opposite sides thereof, and means adjustably interconnecting said pair of additional stands with the first mentioned stand for adjusting each of said additional stands towards and away from the first stand and towards and away from the needle cylinder.

9. A stand assembly for knitting machines, comprising a vertically elongated first stand having a flat base, a bracket adjustably connected to the first stand for adjustable sliding movement laterally thereof, another bracket adjustably connected to the first mentioned bracket for adjustable sliding movement normal to the adjustable sliding movement of the first mentioned bracket, and a second stand carried by the second mentioned bracket and extending vertically upwardly therefrom in laterally spaced relation to said first stand.

10. A stand assembly for knitting machines comprising a vertically elongated first stand having a flat base, a plurality of brackets adjustably connected to the first stand for adjustable sliding movement laterally thereof, another bracket adjustably connected to each of the first mentioned plurality of brackets for adjustable sliding movement normal to the adjustable sliding movement of the first mentioned brackets, and a stand carried by each of the second mentioned brackets and extending vertically upwardly therefrom in laterally spaced relation to said first stand.

11. Apparatus as defined in claim 9, wherein the first mentioned bracket is angular in form, providing a pair of arms disposed substantially perpendicular to each other, one of said arms being slotted to receive a fastener having threaded engagement with the first stand, and the second

bracket being also slotted to receive a fastener having threaded engagement with the other arm of the first mentioned bracket.

12. Apparatus as defined in claim 9, wherein the first stand and the first mentioned bracket are respectively provided with coacting guide means for guiding the first mentioned bracket in its adjustable lateral sliding movement, and said first and second mentioned brackets are also respectively provided with additional coacting guide means for guiding the second mentioned bracket in its adjustable sliding movement relative to the first mentioned bracket.

13. A stand assembly for knitting machines, comprising an upwardly elongated stand member, a slide mounted thereon for horizontal adjusting movement, releasable means coacting with said slide for restraining the slide against movement after adjustment of the same, a cross-slide mounted on the first mentioned slide for horizontal adjusting movement in a direction crosswise to the adjusting movement of the first mentioned slide, and another stand carried by said cross-slide and disposed in generally parallel spaced relation to the first mentioned stand at one side thereof.

14. Apparatus as defined in claim 13, wherein said stands are forked at their upper ends for supporting coaction with the usual equipment to be mounted thereon in operative relation to the needles of the knitting machine.

15. Apparatus as defined in claim 13, wherein a third stand is disposed at the opposite side of the first stand and is connected to the latter by a separate slide and cross-slide generally corresponding to the first mentioned slides.

16. In a knitting machine having a needle cylinder and a support extending about the axis of said needle cylinder at a point below the cylinder, a plurality of stands adjustably mounted upon said support and adjustable as a unit both radially and circumferentially relative to the needle cylinder, and slide means interconnecting said stands for adjustment of certain of said stands laterally relative to each other and radially relative to the needle cylinder independently of the unitary adjustment aforesaid.

17. In a knitting machine having a needle cylinder and a support extending about the axis of said needle cylinder at a point below the cylinder, a plurality of stands adjustably mounted upon said support and adjustable as a unit both radially and circumferentially relative to the needle cylinder, slide means interconnecting said stands for adjustment of certain of said stands laterally relative to each other and radially relative to the needle cylinder independently of the unitary adjustment aforesaid, and means for angularly adjusting certain of said stands independently relative to each other.
